CLAIM

(21) Appl. No.: **29/162,798**

The ornamental design for an arc-shaped loudspeaker housing, as shown and described.

(22) Filed: **Jun. 20, 2002**

DESCRIPTION

(51) LOC (7) Cl. **14-01**

FIG. 1 is a perspective view of my new design;

(52) U.S. Cl. **D14/215**

FIG. 2 is a left side elevational view of my new design;

(58) Field of Search D14/204, 207,

FIG. 3 is a right side elevational view of my new design;

D14/209–216, 356; 181/144–145, 147–148,

FIG. 4 is a front elevational view of my new design;

150, 153, 157, 198–199; 381/300–302,

FIG. 5 is a rear elevational view of my new design;

306, 333, 345, 361–364, 386–388

FIG. 6 is a top plan view of my new design;

(56) **References Cited**

FIG. 7 is a bottom plan view of my new design; and,

U.S. PATENT DOCUMENTS

FIG. 8 is a perspective view showing the embodiment with a protective net.

D407,405 S * 3/1999 Chiu D14/214
D415,159 S * 10/1999 Nakano D14/215

The broken line showing of a protective net is for illustrative purpose only and forms no part of the claimed design.
